UNITED STATES PATENT OFFICE.

TORNEY O. NALL AND ERNEST J. BEAUVAIS, OF ST. PAUL, MINNESOTA.

ADVERTISING AND CALENDAR CLOCK.

Application filed March 13, 1925. Serial No. 15,401.

Our invention relates to advertising calendar clocks and the object is to provide in a single device a novel calendar clock and advertising medium which may to good advantage be placed in banks, drug stores, churches, halls and other public places and may also be used as a house clock.

In the accompanying drawings:

Fig. 1 is a front elevation of the complete device with the outer case or inclosure.

Fig. 2 is a front elevation of the mechanism and its frame removed from the inclosure, the dial and its hands removed, and fragments broken away to expose certain parts.

Fig. 3 is a rear elevation of Fig. 2.

Fig. 4 is a sectional top view on the line 4-4 in Fig. 2, with the paper strip carrying the dates and advertisements omitted and the mechanism frame 76 of the time piece almost entirely closed at its top so as to avoid showing of all the common clock mechanism.

Fig. 5 is a portion of Fig. 4 with the escapement arms 62, 62^a and some other parts omitted.

Fig. 6 is a section on the line 6-6 in Fig. 5, and a portion of the roller 57 and its disc 60 and intermediate frame 29.

Fig. 7 is a section on the line 7-7 in Fig. 4 with top plate 25 of the main frame added.

Referring to the drawings by reference numerals, the outer case or inclosure consists of a bottom 10, top 11, end walls 12, rear wall 13 and front wall 14, the latter hinged at 15 and has a suitable catch 16 and is provided with an aperture 17 with a small door 18 hinged at 19 and held closed by a catch 20. Said small door has a round glass 21 through which is seen the clock dial 22 upon which the hour hand 23 and minute hand 24 indicate the time.

Removably mounted in the case is a main metal frame consisting of a bottom plate 25, top plate 25^x, end plates 26, 27 and a few upright flat frame bars 28, 29, 30, 31 and 32 (see Fig. 4). The clock dial 22 may be secured on the frame bar 32, as in Fig. 4.

The front wall or door 14 is provided with a small sight slot 33 through which is displayed a fixed advertisement 34. Through a larger slot 35 is displayed a long slip of paper 36 having printed upon it the successive days and dates of a year, as indicated in Fig. 1, and to one side thereof a variety

of advertisements in the spaces marked Ad, Ad in Fig. 2. Said strip of paper 36 is guided to move in vertical direction near the sight slots, by two rollers 37-38 (see Fig. 7) and has one end attached to a roller 60 on which the strip is originally wound. The strip is held frictionally by a curved leaf spring 40 to prevent accidental unrolling. The other end of the strip is secured to a winding roller 41 having a shaft 42 with a bevel gear 43 fixed on it (see Fig. 4) and driven by a bevel gear 44, fixed on a shaft 45 having a pinion 46 driven by a gear 47 shaft 48 and spring 49. The latter may be wound by a suitable key put on the stem 50. 51 is the ratchet wheel and 52 the pawl to aid in such winding. Said driving mechanism is mounted in a frame 53 secured to the frame bar 30 and with its frame may be termed a spring motor. 55 and 56 are bearings for the shaft 42.

The spring motor would wind up the entire strip 36 in a few minutes instead of a year. It is therefore controlled by the clock shown and a controlling roller 57. This roller is provided near each end with radial pegs 58 engaging in perforations 59 in the strip, so that the strip can only move and exhibit the next date on it when the clock releases it at midnight, one step each night, by an escapement which in the present illustration is as follows:

At one end of the roller 57 is fixed a disc or wheel 60 having four equidistant teeth 61, each of which when turned upward is engaged by an escapement lever 62, or for better effect, two levers 62 and 62^a are used; both levers pivoted at 63 side by side in a special small frame 64 which consists of two parallel plates, secured together by the pivot 63 and a similar rivet 65. Mounted in this frame is a cam 66 (best shown in Fig. 6) having a tooth 67 wide enough to lift both levers 62 and 62^a above the upper tooth 61^x of disc 60; but it will not lift both levers fully at the same time because each lever has a clearance notch 68 and an angular shoulder 69 forward thereof and as said shoulders are one ahead of the other the result is that lever 62 is first raised and allowed to drop upon the tooth 61^x (see Fig. 7) say fifteen or twenty minutes before twelve-o'clock midnight and more exactly at midnight the cam will have fully raised lever 62^a and thereby permitted the disc 60 to 110

make one fourth of a revolution. The idea of having two levers is that the lever 62 should rest on the disc and be sure to stop the next tooth 61 which is coming so quickly that a single lever might not get time to stop its upward movement and also be drawn downward by gravity to engage the next tooth 61 in time to stop it. But by using a light lever and a spring (not shown) 10 pressing it downward, a single lever may also answer the purpose.

The cam 66 is fixed on a shaft 70 which is journaled in the frame 64 and also in the frame bars 31 and 32, and is fixed in a gear wheel 71 which is twice as large as the pinion 72 driving it and which is fixed on the hour arbor 73 holding the hour hand 23. This will explain that when the hour hand has made two revolutions the gear 71 20 and cam 66 have made only one revolution and will thus allow the calendar to be changed only at midnight by the spring motor operating it.

In Fig. 4, 74 is a spacing collar between the frame 64 and the bar 32 of the main frame and 75 is the shaft carrying the minute hand 24 of the clock.

As for the clock itself it is preferably an eight day clock. Its frame 76 contains the required mechanism of which in the present illustration only the main spring 77, gear 77^a, winding ratchet 78 and escapement 79 and winding stem as 80 or 81 are shown.

In Fig. 3 is shown that the framework may have an aperture 82 through which to reach the stem 80 with a key if it be desired to wind the clock from the rear side. Likewise, a clearance 83 and stem 84 indicate that the clock may have its hands adjusted

from the rear of the device. In said view 40 85 is a guard about the main spring.

At the end of each calendar year the strip 36 is removed and replaced by a new one for the next year, and such new strip may carry the same advertisements as the one displaced, 45 or it may have new and different advertisements; all as may be desired.

All the apertures in the front wall may be closed by either glass, mica or other transparent material. 50

What we claim is:

In a device of the class described, having a motor driven roller and a flexible display strip arranged to be wound upon it from another roller; a controlling roller rotated by the flexible strip and having at one end a disc with radiating teeth spaced to correspond to the items displayed each day by the strip; two horizontally disposed levers having each one end on a pivot, so as 60 to swing side by side in vertical planes and resting normally upon the upper edge of the disc so as to obstruct its rotation by contacting with its teeth; each of said levers having its lower edge provided with a shoulder disposed one nearer than the other to the pivot; a cam shaft having a fixed cam arranged to engage and raise said shoulders one shortly after the other; a gear fixed on the cam shaft, a clock, a pinion fixed on the 70 hour-hand arbor of the clock and meshing with said gear, said pinion being half the diameter of the gear, so as to cause the cam to act only once in twenty-four hours.

In testimony whereof we affix our signatures.

TORNEY O. NALL,
ERNEST J. BEAUVAIIS.
